UNITED STATES PATENT OFFICE.

RICHARD K. HOHMANN, OF SAN DIEGO, CALIFORNIA.

PRESSER-FOOT FOR SEWING-MACHINES.

1,036,845.

Specification of Letters Patent. Patented Aug. 27, 1912.

Application filed November 9, 1910. Serial No. 591,499.

To all whom it may concern:

Be it known that I, RICHARD K. HOHMANN, a citizen of the United States, and resident of San Diego, in the county of San Diego and State of California, have invented certain new and useful Improvements in Presser-Feet for Sewing-Machines, of which the following is a specification.

This invention relates to a presser foot for sewing machines, and it has been my object to make a presser foot which will so distribute the pressure upon the goods being operated on as to cause the material or the goods to be fed forward by the feed bar uniformly without doubling or puckering even where the material is very flimsy or light.

The novel features of the invention will be apparent from the following description taken in connection with the accompanying drawings.

In the drawings,—Figure 1 is a side view of my presser foot together with the associated parts of a sewing machine; Fig. 2 is a similar view with the feed bar in its lowered position; Fig. 3 is a detail perspective view of the presser foot; Fig. 4 is an enlarged longitudinal section of the presser foot; and Fig. 5 is a plan view showing the feed bar in dotted lines.

I have found that in using an ordinary presser foot particularly on very thin material, there is likely to be puckering of the material so that a smooth seam is not formed, and I have discovered that this puckering can be prevented by applying somewhat greater pressure on the material immediately in the rear of the needle bar, so that the feed bar will have a better grip on the material at this point. I have therefore made the presser foot with a movable and yielding part in line with the needle passageway and in the rear thereof, so as to secure greater pressure at that point.

In the drawings, 1 represents the bar which is yieldingly pressed downward in the sewing machine, and which carries at its lower end the presser foot 2.

3 represents the throat plate which has in it the opening 4 beneath the presser foot, in which opening works the feed bar 5 which may be of usual form. This feed bar is made up of longitudinal rows of teeth facing in the direction in which the cloth is to be fed, and the central row being shorter than the side rows. This feed bar is given

longitudinal movement and also the usual up and down movement by any usual connection, such as the bar 6.

The presser foot, as shown in the drawings, is made up of a body portion having a longitudinal slot 7 in its forward part to provide a passageway for the needle, and in the particular form shown the rear part has a slot 8 as a convenient means for attaching it to the lower end of the bar 1. Immediately in the rear of the slot 7, and in the lower face of the presser foot I form a groove 9 longitudinally of the presser foot and in line with the slot. In this groove I place a small piece or plate 10 which has the rounded forward and rear edges, and which is adapted to be pressed up into the groove so that its lower face will be flush with the lower face of the presser foot. The limit of the inward movement of the plate is reached when it strikes the bottom of the groove 9 and at that time its face is flush with the balance of the presser foot. Two pins 11, 12 are attached to this piece 10 and extend upwardly through the presser foot, being connected above the presser foot by the bar 13. Thus the pins guide the piece 10 in its up and down movement, and the connecting bar 13 serves as a stop to limit the downward movement of the piece. A U-shaped spring 14 is secured at its ends on opposite sides of the slot 7 extending to the rear and bearing on top of the connecting piece 13, so as to tend to hold the plate 10 in its lowered position, as shown in Fig. 4.

It will be observed that the yielding plate 10 will bear down on the material directly in the rear of the needle, and it will coöperate with the short central row of teeth 15 in feeding the material forward, and thus the material will be pressed against the short row of teeth with greater pressure than against the long side rows. The result of this is that the central portion of the material immediately behind the needle is fed forward at the same speed as the portions at the side, and there will be no puckering even where the material is very thin.

Having thus described the invention, what is claimed is:

1. A presser foot for sewing machines comprising a body portion having a passage-way for the needle in advance of the rear portion thereof, and means at the rear of said passage-way and in line therewith for exerting greater pressure upon the por-

tions of the material containing stitches than on those portions of the material under the presser foot at the sides of the stitches.

2. A presser foot for sewing machines comprising a body portion having a passage-way for the needle in advance of the rear portion thereof, and yielding means at the rear of said passage-way and in line therewith for exerting greater pressure upon 10 the portions of the material containing stitches than on those portions of the material under the presser foot at the sides of the stitches.

3. A presser foot for sewing machines 15 comprising a rigid body portion adapted to engage the cloth having a passage-way for the needle, and having rigid rear side extensions, and a central spring pressed portion at the rear of said passage-way and in 20 line therewith between said rear extensions, the said spring pressed portion normally projecting below the lower surface of said presser foot under the influence of the spring and adapted to be pushed back only so far 25 as to be flush with said surface and tending at all times to project downward under the influence of the spring.

4. A presser foot for sewing machines, comprising a rigid body portion provided

with a longitudinal slot in the forward part 30 for the needle and a groove in the under surface in line with said slot at the rear, a movable piece fitting in said groove and adapted to occupy a position flush with said under surface when pushed inward to the 35 limit of its movement, yielding means operative at all times for pressing said movable piece downward, and means for limiting the downward movement of said piece.

5. A presser foot for sewing machines 40 comprising a body portion provided with a longitudinal slot in the forward part for the needle and a groove in the under surface in line with said slot, a movable piece fitting in said groove and adapted to occupy a position 45 flush with said under surface, guide pins on said piece extending through said presser foot, a connecting piece for said pins above said presser foot serving as a stop, and a spring bearing down on said connecting piece.

In testimony whereof I affix my signature in presence of two witnesses.

RICHARD K. HOHMANN.
